UNITED STATES PATENT OFFICE.

GEORGE ALEXANDER, OF JAMAICA, AND ROBERT JOHNSON, OF BROOKLYN,
NEW YORK.

CLOTHES-RACK.

SPECIFICATION forming part of Letters Patent No. 465,551, dated December 22, 1891.

Application filed March 16, 1891. Serial No. 385,149. (No model.)

To all whom it may concern:

Be it known that we, GEORGE ALEXANDER, residing at Jamaica, Queens county, and ROBERT JOHNSON, residing at Brooklyn, 5 Kings county, State of New York, both citizens of the United States, have invented certain new and useful Improvements in Racks and Extensible Standards Therefor, of which the following is such a full, clear, and exact 10 description as will enable any one skilled in the art to which it appertains to make and use the same, reference being had to the accompanying drawings, forming part of this specification.

15 Our invention consists in the various novel and peculiar combinations and arrangements of the several parts of the rack and the extensible standard, all as hereinafter fully described, and then pointed out in the claims.

20 In the accompanying drawings of a rack and extensible standard made in accordance with our invention, Figure 1 is a side view thereof, with the bracket for the hanger-arms, the adjustable clamp for the standard, 25 and the upper part of the lower member of the standard shown in central vertical section, and with the hanger-arms broken away at their outer ends, the hanger-arm at the right-hand side of the view being illustrated 30 as adjusted in position of use, while that at the left is lowered into position of disuse.

Fig. 2 is a view of a section taken on a plane indicated by line 2 2, Fig. 1, and looking in the direction of the adjacent arrow, the 35 hanger-arms of the rack being adjusted in position of use. Fig. 3 is a view of a section taken on a plane indicated by line 3 3, Fig. 1, and looking in the direction of the adjacent arrow. Fig. 4 is a view of a section 40 taken on a plane indicated by line 4 4, Fig. 1.

Referring to the drawings, in which like numbers of reference designate like parts throughout, the number 5 designates a post or pillar. (Shown as preferable in an up-right position.) This post 5 is provided with an extended base 6, of any suitable and preferred shape, which is designed to rest upon any stationary or firm object, such as a shelf or the floor 7 of a room. A second post or 45 member 8 is mounted upon the post 5, par-

allel therewith, and is vertically adjustable thereon, the two said posts or members together constituting an extensible standard 5 8. The upper end of post 8 is provided with a broad flattened part or head 9, affording an 55 extended surface for engaging with an overhead fixture or the ceiling 10.

The two posts or members 5 8 are adjustably secured together by the following means: The upper post 8, which is mounted, preferably, upon the side of post 5, has a clamp 11, secured fast thereto, and consisting in a yoke 12, passing around the post 8 and secured thereto by a suitable screw 13 or otherwise, and arranged obliquely at an angle of about 60 forty-five degrees. This yoke of the clamp embraces the post 5, and is provided with an obliquely-arranged set or tension screw 14, which works in a screw-threaded opening 15 in the yoke. The foot of the screw 14 engages with the series of notches or teeth of a suitable rack 16, arranged longitudinally of the post upon the opposite side thereof from where the upper post 5 is mounted. By releasing the screw 14 and sliding the post 8 up 65 or down the standard may be accordingly lengthened or shortened, and may be then held in such adjustment by turning the screw 70 down so as to bind against the tooth opposite to it. Both faces of the teeth of the rack 16 75 are inclined so that the foot of the set-screw 14 may bear flatly against the inclined faces 17 of the teeth. After the standard has been adjusted to fit between two fixed objects—such as the floor 7 and the ceiling 10—it may 80 be held in such position under tension by forcibly turning down the screw 14, as will be readily understood from Fig. 1. The rack 16 is sunk in the side face of the post 5 and does not project beyond the surface thereof, 85 so that it affords no obstruction to the clamp in adjusting the standard. In this way the standard may be secured in position in a suitable place, so that it cannot be tilted or even moved out of place. At the same time it can 90 be readily released and removed and set up in another place, as desired.

In order to give greater vertical stability to the adjustable post 8, we set the same in a groove 18, formed longitudinally of the lower 95 100

post 5, and we also provide the upper part of post 5 with a strap 19, through which the upper post 8 loosely passes.

Upon the upper post 8 is mounted a bracket 20, formed with a central opening 21 for loosely receiving the cylindrical post 8, along which it may be adjusted. The bracket is made, preferably, circular in shape, though it may be made to assume any desired shape. A series of radially-arranged slots 22 is formed in the outer edge or periphery of the bracket, and across each slot, near its outer end, is placed a hinge-pin 23. As the slots 22 are close together, the hinge-pins 23 are conveniently provided by sinking a wire or metallic rod in a groove 24, cut in a circumferential edge of the bracket, as will be understood from Fig. 3.

In each slot 22 is hung a movable hanger-arm 25, which is formed with a longitudinal slot 26, the plane of which is at right angles to the axis of the hinge-pin. This hinge-slot or elongated eye 26 of the hinge-arm may be formed in the material of the arm itself, though we have shown it as formed, preferably, by means of a wire loop or staple 27, which is secured in one side of the arm near its end. This slot 26 is provided for the end-wise movement or reciprocation of the hanger-arm in addition to its swinging movement on its hinge-pin, so that when the arm is swung from its depending position, as shown at the left of Fig. 1, into about a horizontal position, as shown at the right of said figure, it may be held in such latter position by pushing the rod inwardly on its length toward the center of the bracket 20 until its inner end takes under a ledge or lip 28, which is disposed near the inner end of each of the slots 22. This locking-lip 28 is shown as a continuous circular part of the bracket and is made in one piece therewith, though it need not necessarily be so made. By moving the hanger-arms and placing them as just described they are firmly set in horizontal position for use, as shown at the right hand of Fig. 1, and in this position they will serve to sustain the weight of any articles or goods with which they are designed to be used. The hanger-arms may, of course, be made to project at a slight inclination to the horizontal when adjusted for use, and may be constructed in any desired shape and of any desired length, the lengths shown being somewhat out of proportion to the height of the apparatus as the arms are broken off at their outer ends for the convenience of illustration.

After the arms 25 are adjusted for use provision is made for locking them against end-wise displacement by means of a notch 29, formed in the edge of each arm near its end, and a rib or projection 30, extending from the under side of the locking-lip 28, the ends of the arms being rounded at 40, in order to slide easily over the rib when being adjusted for use. This rib 30 is extended in a circle

about the central opening of the bracket upon the under side thereof, and may be formed integral with it, as shown.

The rack may be adjusted to any height on the standard, such adjustment being controlled by means of a cord or cords 31, which pass from fixed points 32 on the bracket 20 over guide-pulleys 33, arranged near the head of the standard, thence down to near the base of the standard, where the cords are provided with a fastening device, consisting in an eye or ring 34, secured to the cords, and a hook or pin 35, fixed near the base of the standard. As the rack carried by the standard is revoluble thereon, the frame or block 36, in which the guide-pulleys 33 are set, is mounted upon the standard, so as to revolve also. The cords 31 are conveniently passed through perforations 37, extending vertically through the bracket 20, one at either side of the central opening thereof. In this way the guide-pulley mounting may be revolved with the rack.

If desired, there may be a vertically-arranged series of fastening-pins 35, placed on the lower part of the standard, so that the rack may be held in different vertical adjustments.

The rack and standard are to be made of suitable materials, partly of wood and partly of metal, as preferred. The bracket 20 of the rack may be turned down from a single piece of wood, or may be formed of a single metallic casting. The standard may be used with any character of rack, and when extended to fit snugly in between two fixed objects—for instance, the ceiling and floor—it may be readily secured in such position under tension by tightening the screw 14. Instead of securing it between the ceiling and floor, it may be set between two suitable projections or shelves, and wherever it may be placed it can be secured against tilting over by reason of its being jammed or forced in between two fixed objects.

The rack may be used for the purpose of displaying or exhibiting articles of goods in stores or for drying clothes, or for any similar and suitable purpose.

Since the hanger-arms may be folded in closely to the standard and the latter shortened considerably, the entire device can be packed up in a small compass for storage or for transportation.

Instead of having the arms 25 arranged over an entire circle, only half the number may be used, and the same set on a half-circle in cases where it is desired to set the apparatus in close to a wall.

Having thus described our improvements in racks and extensible standards therefor, what we claim as our invention, and desire to secure by Letters Patent, is—

1. The combination of an extensible standard comprising a vertical post or member provided with a longitudinally-disposed rack or series of notches having inclined faces, and a

second post or member vertically adjustable thereon and provided with an obliquely-arranged tension-screw adapted to engage the inclined faces of said rack or notches, the said 5 latter post or member provided with a set of hanger-arms and adapted to engage with its upper end a fixed point—for instance, the ceiling—whereby the standard may be set in fixed position, for the purpose set forth.

10 2. The combination of two posts or members adjustable lengthwise on each other, one of said members provided with a longitudinally-disposed rack formed with teeth having inclined faces, the other said member provided 15 with a releasable adjusting-clamp consisting in a yoke or collar mounted obliquely thereon and embracing the said first member and provided with a set-screw disposed obliquely in the yoke, and its foot adapted to engage flatly 20 one of the inclined faces of the teeth, substantially as and for the purpose set forth.

3. The combination, with a post or standard, of a rack having hanger-arms, and provided with a bracket 20, formed with a cen-

tral opening 21 for receiving the post, said 25 bracket being revoluble and vertically adjustable upon the post of a cross arm or block 36, provided with a central eye for receiving the post and mounted thereon at the head of the post, so as to revolve in the horizontal, a 30 guide-pulley 33, arranged at each end of the arm or block 36, and cords 31 31, secured each by one end to the bracket 20, and passing over said pulleys 31 31 downwardly toward the base of the post or standard, where they 35 are provided with a releasable fastening device, substantially as and for the purpose set forth.

In testimony whereof we have hereunto set our hands and affixed our seals this 9th day 40 of March, 1891, in the presence of the two subscribing witnesses.
